Primary Examiner — Lauren D McVey*Assistant Examiner* — Elisa Maria Pujals(74) Attorney, Agent, or Firm — Duane Morris LLP(57) CLAIM

The ornamental design for a bottle golf tee, as shown and described.

DESCRIPTION

FIG. 1 is a perspective view of a bottle golf tee with environment;

FIG. 2 is a front elevation view without environment;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof; and,

FIG. 8 is a perspective view of the bottle golf tee of FIG. 1 without environment.

The broken lines shown in FIG. 1 illustrating a golf ball are directed to environment and form no part of the claimed design. Additional broken lines show portions of the bottle golf tee which form no part of the claimed design.

1 Claim, 8 Drawing Sheets(56)
